UNITED STATES PATENT OFFICE

ROLAND BROCKWAY JONES AND CYRUS FREDERICK JONES, OF OREGON, ILLINOIS

DESIGN FOR A SLED COASTER

Application filed February 14, 1931. Serial No. 38,669. Term of patent 14 years.

To all whom it may concern:

Be it known that we, ROLAND BROCKWAY JONES and CYRUS FREDERICK JONES, both citizens of the United States, residing at Oregon, Illinois, in the county of Ogle, State of Illinois, have invented a new, original, and ornamental Design for a Sled Coaster, of which the following is a specification, reference being had to the accompanying drawing, forming a part thereof.

Fig. 1 is a plan view showing our new design;

Fig. 2 is a side elevational view; and

Fig. 3 is a front elevational view.

We claim:

The ornamental design for a sled coaster, substantially as shown.

ROLAND BROCKWAY JONES.
CYRUS FREDERICK JONES.
